UNITED STATES PATENT OFFICE.

CARL F. HJERPE, OF JAMESTOWN, NEW YORK.

TALKING MACHINE.

Application filed August 11, 1922. Serial No. 581,215.

To all whom it may concern:

Be it known that I, CARL F. HJERPE, a citizen of the United States, residing at the city of Jamestown, in the county of Chautauqua and State of New York, have invented certain new and useful Improvements in Talking Machines, of which the following, taken in connection with the accompanying drawings, is a specification.

10 This invention relates to improvements in talking machines and more particularly to the type of machine provided with a plurality of amplifiers.

One object of this invention is to provide 15 a talking machine equipped with two inverted amplifiers connected to each side of a specially constructed sound box, the structure of the amplifiers including movable parts so that two independent motions, horizontal and vertical, will be made with the same ease as with one amplifier, while at the same time the sound channels or sound passages in both amplifiers are continuous and lead independently of each other, one from 20 each side of the sound box to the mouths of the amplifiers.

For a full, clear and exact description of 25 a talking machine embodying this invention with two amplifiers reference is made 30 to the following specification and to the accompanying drawings which form a part thereof, and in which—

Figure 1 is a front elevation of the talking machine embodying one form of my improved construction, partly in section.

35 Fig. 2 is a transverse sectional view of the machine illustrated in Fig. 1.

Fig. 3 is a plan view thereof with the cover removed.

40 Fig. 4 is an enlarged sectional view taken along line 4—4 of Fig. 3.

Fig. 5 is an enlarged sectional view taken along the line 5—5 of Figs. 3 and 4.

Fig. 6 is a plan view partly in section of 45 the two tone arms, elbows, sound tubes, sound box and pivot block.

Fig. 7 is a sectional view taken along line 7—7 of Fig. 6.

Fig. 8 is a side view of the plates which 50 hold the elbows together.

Fig. 9 is a side view of the damper in each sound tube.

Fig. 10 is a similar view of the damper taken at right angles to Fig. 9.

55 Fig. 11 is a sectional fragmentary view

of the sound tube, showing the damper inside of the sound tube.

Fig. 12 is a plan view of a short piece of tubing with a semi-circular notch in the upper side, said tubing forming a sleeve on the 60 sound tubes.

Fig. 13 is a plan view of the sound tube with the tubing or sleeve of Fig. 12 withdrawn, showing the long notch into which the knob on the damper passes and also the 65 shoulder against which the short tubing of Fig. 12 fits when the damper is in place as shown in Fig. 11.

Fig. 14 is a plan view of the sound tube showing the short tubing of Fig. 12 in 70 place on the sound tube, the damper being omitted.

Fig. 15 is a side view on a smaller scale 75 of the pivot block to which the two tone arms are fastened, one on each side of the pivot block, two projections on each side being formed to guide the tone arms into position and,

Fig. 16 is a front view on a smaller scale 80 of the pivot-block.

Referring to the drawings, the reference numeral 11 is used to indicate the cabinet of a talking machine embodying my invention, which may be of any desirable character, and which is preferably provided 85 with a lid 10, and compartments 12 for the reception of the records, which compartments may be altered to keep a radio receiving set. Contrary to conventional construction, the cabinet is also provided with a 90 plurality of amplifiers 13, the sound waves emanating from the latter being capable of being regulated by the dampers 51 provided with the knobs 54 by which the damper is 95 regulated as will be described below.

The upper sections 13^a of the amplifiers inside the cabinet run straight down from the upper part 14 of the cabinet to about half way between the upper part 14 and the lower part 15 where a horizontal partition board 16 made of several plies of veneer glued together is mounted. Through the board 16 are formed passages 17 slightly conical and coinciding with the contour of the amplifiers.

The lower sections 13^b of the amplifiers 13 run from the under side of the horizontal partition board 16 with a slight curving downward and forward toward the bottom 100 and the front of the lower part of the cabi- 105

net, and at the same time the lower sections 13^b widen gradually until they reach the front of the cabinet, forming ovals with the longer axis vertical at the mouths 13^c.
6 Sections 13^b of the amplifiers are made from plastic composition.

10 The upper ends of the sections 13^a are fixed in position by collars 21 which are held by screws in the strip 18, while the lower ends are held in position by similar collars 22.

15 Mounted on the board 19 is a block 23 in which are formed sound conduits 24, each being in alignment with an amplifier so as to form a continuous sound channel from the receiving ends of the conduits to the mouths of the amplifiers. The receiving ends of the conduits are horizontal, the conduits being so formed that the end of 20 one is below and faces the end of the other.

25 Between and connected to the conduits is a pivot block 25 which carries at each side a tone arm 26. The block is swivelled on the block 23 by means of arms 27 which project from the pivot block 25, and terminating above and below the block 24, are secured thereto by screws 28. In the pivot block 25 are formed curved passages 29 which connect the ends of the tone arms 30 26 to the mouths of the conduits 24.

35 As shown particularly in Fig. 4, a gasket 30 is mounted on a shoulder 31 surrounding the mouth of each conduit 24 to prevent any leakage of sound from the joiners 40 of the pivot block and conduit block which joiners must permit an oscillation of the movable pivot block relative to the stationary conduit block. The ends of the tone arms 26 seat in recesses 32 at the ends of the passages 29 and are held in position by bolts 33 through ears 34 projecting from the tone arms and block. Thus the pivot block is allowed to oscillate in unison with the tone arms without interfering with the 45 connection from the arms to the conduits, and hence the sound waves pass freely from the tone arms to the mouths of the amplifiers.

50 At the outer ends of the tone arms 26 are secured elbows 35, each of which has a lug 36 projecting inwardly in alignment. The contacting surfaces of the tone arms and elbows are correspondingly flanged so that the connections between them are leak 55 proof and the elbows are so held by means of a member 37 attached to both lugs 36. The member 37 comprises a block 38 to the opposite sides of which are secured plates 39. When the elbows are joined, the member 37 is placed with the block 38 between the lugs and the plates 39 extending at each side. In the plates are formed bolt holes 60 40 which, when the parts are assembled, lie at each side of the slots or enlarged holes 65 41 of the lugs 36. Bolts 42 passed through

the holes 40 and slots 41 clamp the plates 39 against the lug and hold the elbows 35 against the tone arms 26. By reason of the slots 41 the relation of the lugs 36 with regard to the plates 39 can be regulated as desired. 70

Carried by the elbows 35 are the sound tubes 43 which enter the flanged openings in the elbows and are held in position by any suitable means, set screws 44 being shown in the drawing. Each sound tube 43 is curved through ninety degrees and has at the upper end a longitudinal slot 45 which terminates in a semi-circular notch 46 in a collar 47 rigidly secured to the tube 43. Over the notched end of the tube 43 is placed a tubing 48 having a semi-circular notch 49 which co-acts with the notch 46 of the collar 47 to form a circular hole 50 which surrounds the stem of a damper 51. 85 The damper 51 comprises a circular plate 52 mounted on a stem 53 and having a knob 54 at the center end of the stem by which the damper may be controlled. At the lower edge of the plate 52 is formed a tip 55 which seats in a pocket 56 in the wall of the tube 43. A collar 57 on the stem 53 co-acts with the tip 55 to hold the damper in position. The dampers above described control the passage of sound waves through 90 the elbows so that the volume desired at any time can be obtained. 95

100 Mounted in a flanged opening 58 in the assembly board 19 is the motor board 59 by which the motor (not shown) is supported in the usual way and on which is rotatably mounted the turn table 60. In order to prevent the communication of the motor vibration to the assembly board 19 the motor board 59 is separated from the assembly 105 board by strips 61 of soft rubber.

110 The sound box 62 which is carried by the sound tubes 43 is completely enclosed by the casing walls 63, 64 from which projects the holder 72 for the needle 82.

At the center of each wall 63 and 64 is formed a flanged opening 84 in which the ends of the sound tubes 43 are fixed by set screws 85.

115 This sound box is set forth in detail in my copending application, Serial No. 644, 292, filed June 8, 1923, as a division of this application.

120 In order to assist in supporting the elbows 35, sound tubes 43 and sound box 62 and to prevent the needle 82 from leaning too heavily upon the record a support 86 is provided between the tone arms 26 to which is secured one end of a spring strip 87. The other end of the strip 87 is fixed under the plates 39 and the block 38 of the member 37. Thus any excessive tendency of these parts to rotate relative to the tone arms will be opposed. A set screw 88 mounted in the support 86 and bearing against the strip 87 130

may be used to enhance or decrease the action of the strip as desired. A plate 89 carried by the support 86 is intended to actuate an automatic stop mechanism (not shown).

The parts attached to the tone arms may be removed if desired and replaced by a specially constructed loud speaking receiver for radio music.

10 In front of the amplifiers 13 are provided doors 90 preferably of grille work backed by screening. These doors are made in sections hinged together so that they can be opened to any desired amount allowing the 75 emission of the sound waves from the amplifiers. The doors 91 of the record compartment 12 are similarly made so the cabinet will have a uniform appearance.

It will be noted that the sound box, sound 20 tubes and elbows move vertically by reason of the connection between the elbows and the tone arms and further that they move horizontally by reason of the connection between the pivot block and the conduits and 25 further that these movements do not in any way interfere with the passage of sound waves to the amplifiers. Moreover, all the passages traversed by the sound waves are curved so that they present no acute angles 30 which would reduce the volume of sound. Thus the tone waves flowing from the amplifiers are pure and mellow but can be effectively regulated by means of the damper mechanism above described.

35 Under ordinary conditions a soft needle can be relied upon to reproduce the desired tone which will be materially enhanced by the use of a loud needle in excess of the volume derived from the conventional machine. By the use of the construction above 40 set forth there will be provided two distinct and independent series of sound waves which will not intermingle with or counteract each other, so that the waves emerging from the 45 amplifiers produce a volume of tone of great purity and power.

While one embodiment only has been shown, and described, I am not to be limited thereby since it will be understood that other 50 modifications may be made without departing from the spirit and scope of my invention as set forth in the following claims.

Having thus set forth my invention what I claim as new and for which I desire the 55 protection of Letters Patent is:—

1. In a talking machine, a sound box, a pivot block having two independent passages therethrough, independent tone arms connecting one end of each passage with 60 said sound box and independent sound conduits mounted upon said block each in alinement with the other end of each passage.

2. In a talking machine, a sound box, a 65 pivot block having two independent pas-

sages therethrough, one passage terminating at the top and side of said block, and the other passage terminating at the bottom and opposite side of said block, independent tone arms leading from said sound box and 70 secured to the sides of said block in alinement with the passage openings therein and independent sound conduits pivotally connected to the top and bottom of said block in alinement with the passage openings therein whereby said block and tone arms can be moved relatively to said sound conduits in a horizontal plane.

3. In a talking machine, two sound conduits, the receiving ends of which are in parallel planes, one directly below and facing the other, a block pivotally mounted upon and between the receiving ends of said sound conduits, said block having independent passages leading from said conduits to 80 opposite sides of said block, independent tone arms fixed to said block in alinement with the passages therein, each of said tone arms being made in two sections pivotally joined in vertical planes and sound tubes 85 mounted in said outer sections connected to said sound box whereby said pivot block, said tone arms, said sound tubes and said sound box can be moved relatively to said conduits in a horizontal plane and said outer 90 sections of said tone arms, said sound tubes, and said sound box can be moved relatively to said inner sections of said tone arms, said pivot block and said conduits in a vertical 95 plane.

4. In a talking machine, sound tubes, each provided with a shoulder near one end and having a notch from the end of each sound tube to said shoulder, a short tubing forming a sleeve mounted on the end of 100 said tube and resting against said shoulder, a damper in said tube having a stem projecting through the notch in said tube, said sleeve having a notch for said stem, a tip on said damper, a pocket in said tube for 105 said tip, whereby said tip forms a pivot for said damper and said sleeve holds said damper in place.

5. In a talking machine, a pivot block, curved brackets integral with said block, a 110 screw threaded in the end of each bracket and having a non-thread portion, said screws being on opposite sides of said pivot block and in alignment with each other to form a pivotal support for said block.

6. In a talking machine, a sound box, a pivot block, sound conduits between the receiving ends of which said block is located, tone arms connecting said sound box to said 115 pivot block and brackets fixed to said block said brackets being pivotally supported upon said sound conduits to permit a horizontal movement of said box, block and tone arms.

7. In a talking machine, a plurality of 120

- sound conduits, brackets pivotally mounted upon said conduits, and a pivot block between said conduits rigidly supported by said brackets.
- 5 8. In a talking machine, a sound box, a pivot block, two tone arms connecting said box to said block, two sound conduits conducting the sound waves from said pivot block, one of said sound conduits being connected to the upper face of said block and the other being connected to the lower face of said block.
- 10 9. In a talking machine, an assembly board, a pivot block, two sound conduits conducting the sound waves from said block, one of said conduits running from the upper face of said block to said board.
- 15 10. In a talking machine, an assembly board, a pivot block, two sound conduits
- conducting the sound waves from said block, 20 one of said conduits running from the lower face of said block to said board.
11. In a talking machine, an assembly board having separated passages there-through, an integral block mounted upon 25 said board, separate conduits formed in said block connecting with said passages separate tone arms and means connecting one of said arms with one of said conduits and the other of said arms with the other of said 30 conduits.

In testimony whereof I have affixed my signature in the presence of two witnesses.

CARL F. HJERPE.
